UNITED STATES PATENT OFFICE

GUNNAR ROSENQVIST, OF PITTSBURGH, PENNSYLVANIA

METAL HEAT RADIATOR

Application filed May 1, 1930. Serial No. 448,887.

This invention relates to a method of making hollow metal bodies of galvanoplastic metal and more particularly to heat radiators for buildings, automobiles and the like. 5 It is among the objects of this invention to provide a method of making radiators which shall be simple and inexpensive and which shall employ no expensive molds or other apparatus heretofore necessary to the 10 fabrication of large articles of galvanoplastic metal by electrolytic process.

Another object of the invention is the provision of a radiator design having relatively large radiating capacity in proportion to 15 its cubical dimensions.

A further object of the invention is the provision of a heat radiator embodying a composite structure consisting of a series of 20 sheet metal tubes having integrally formed galvanoplastic metal portions constituting heat radiating fins.

These and other objects of the invention will become more apparent from a consideration of the accompanying drawings in 25 which like reference characters designate like parts and in which Fig. 1 is an end view of a pair of sheet metal plates assembled and prepared in accordance with the principles of this invention; Fig. 2 a side elevational view thereof; Fig. 3 a top plan view partially in section, of a completed radiator structure taken along the line III—III of Fig. 4; Fig. 4 a side elevational view of the structure shown in Fig. 3; Fig. 5 a horizontal sectional view of the 30 radiator structure shown in Fig. 3, showing the fins partly opened; Fig. 6 an end view of a prepared plate of sheet material for making a radiator, which is a modification 40 of that shown in Fig. 1; Fig. 7 a similar view of the finished radiator section; Fig. 8 a side elevational view of a pair of plates of sheet material for making radiators for automobiles; Fig. 9 an end view of the 45 expanded radiator, tube and fin structures; and Fig. 10 an end view of Fig. 8.

Referring to Figs. 1 to 5 inclusive of the drawings, the structure therein illustrated 50 comprises a pair of sheet metal plates 1 and 2 of copper having a layer of adhesive

material such as resinous varnish 3 therebetween, the metal being of thin gauge and the varnish functioning to hold them together during the process of fabrication.

A bead or stripe 4 of a syrupy substance 45 which is soluble in water, such for example as dissolved sugar, is laid in stripes as at 4 and along the edges 5 and 6 on both sides of the joined sheets. After applying these stripes the joined plates are dipped in a 60 preparation of wax and gasoline and are dusted off with graphite flakes or other conducting material thereby coating both sides of the doubled sheet.

As shown in Figs. 2 and 4, the plates 1 65 and 2 are provided with a plurality of perforations or slots 7 in longitudinal alignment forming a row in spaced relation, the perforations being made either before or after the sheets are coated with the conducting material. If the perforations are made after the sheets are coated, the stripe 4 of the soluble material may be dispensed with since the shearing edge of the 70 perforating die produces a clean metal surface 75 around the entire edge of each slot.

Stripes 8 of a suitable insulating material, such as an insulating varnish, are formed between the rows of perforations 7 and extending the overall outside length of the 80 row. Stripes 9 are then formed between the top and bottom stripes 6 and the ends of the stripes 8, running the entire length of the sheets between the end stripes 5. Insulating stripes 10 are also applied between 85 the slots conforming to their width and all the stripes 8, 9 and 10 are formed on both sides of the joined sheets.

The prepared plates are then submerged 90 in water or other solvent to dissolve the sugary substance, which when dissolved exposes additional clean surfaces of copper in lines or stripes corresponding to stripes 5 and 6.

The sheets or plates are next suspended 95 in an electrolytic solution and a copper deposit of suitable thickness is made on the graphite coated portion and the exposed copper in a well known manner. The stripes 8, 9 and 10 being of an insulating material, 100

break the continuity of the copper deposit on the surfaces of sheets 1 and 2 and by turning up the edges of the deposited material at the insulated portion 7, a structure 5 as shown in Figures 3, 4 and 5 is formed.

The deposited copper constitutes heat radiating fins 11 which are integrally joined at and across the edges of perforations or slots 7, as at 12. The intervening portions 10 of sheets 1 and 2 are then separated or expanded to form the tubes 13, communicating passages 14, and the tubes communicating with top and bottom chambers 15. The fins 11 may be opened to any angle such as shown 15 in Figs. 3 and 5 and the tubes may be connected in the customary manner to a steam or hot water heating system. It is evident that the large fins 11 integrally joined with the tubes 13 provide a very large heat 20 radiating surface for the relative overall dimensions of the structure.

In Figs. 6 and 7 is shown a modified form 25 of the radiator illustrated in Figs. 1 to 5 inclusive. A single sheet metal plate is coated with the soluble stripes 4. The sheet 30 is then dipped, as in the double sheet structures, in the wax preparation and dusted off with graphite flakes, thereby coating both sides, as explained above. Stripes 8 of insulating material are formed on one side 35 of the sheet between the stripes 4 and the prepared sheet is then submerged in water to dissolve the stripes 4, leaving corresponding stripes of clean copper surfaces. The 40 sheet is next subjected to the galvanoplastic process described herein with reference to Figs. 1 to 5 inclusive, to form the fins 11 on one side and one wall of the tubes 13. The fins 11 may be opened to any angle 45 such as shown in Fig. 7, and the tubes are joined at the top and bottom and provided with the customary connections for the heating system.

In Figs. 8 to 10 of the drawings, I have 45 shown a radiator suitable for the cooling of engines of automobiles. I employ substantially the same process but apply it differently to produce a structure suitable for the purpose. The two sheets 1 and 2 joined 50 by a resinous substance 3 are employed as in the other type of radiator. The sheets are not perforated but the stripes 4 of the sugary substance are applied wherever it is desired to form a deposit integrally with 55 the sheets 1 and 2. In Figs. 8 and 10, such deposits are shown in spaced relation and terminate short of the edges 16 and 17. The edges are likewise coated with this substance forming beads 18 and are then submerged 60 in dissolved wax and coated with graphite flakes or other suitable conducting material. Stripes 8 of an insulating material are formed between the ends of stripes 4 and along the stripes 18, and the prepared sheets 65 are then submerged in water to dissolve the

stripes 4 and 18 which leaves the striped portions clean.

By submerging the sheets in an electrolytic solution and constituting them a cathode through proper electrical connections, a deposit of copper of a suitable thickness is made which covers the entire surface area of both other faces of the joined sheets, except over the beads 8, though including edges 16 and 17. 70

There are no deposits over the insulating beads 8. The edges 16 and 17 are joined together and the deposited material is joined integrally with the sheets 1 and 2 at the exposed stripes 4 and 18. 75

By expanding the sheet-like deposited substance in the manner shown in Fig. 9, a radiator core structure is formed comprising the tube 19 and the internal fins 20. The tube 19 is formed by separating the sheets 1 and 2 between edges 16 and 17 by the application of hydraulic pressure. 80

It will be evident from the foregoing that the electrolytically deposited fins 20 are integrally joined with the tube 19 thus providing a most efficient and effective heat conducting joint for dissipating the heat of the tube. The radiator core structure may be built up of the units shown in Fig. 9 or such units may be integrally formed by arranging any number of sheets in spaced relation and joining them by the galvanoplastic metal. 85

It is evident from the foregoing description of this invention that radiators made in accordance therewith provide a maximum heat radiating surface with a minimum use of material and space, and that such radiators are of inexpensive construction. 90

Although several embodiments of the invention have been herein illustrated and described, it will be evident to those skilled in the art that various modifications may be made in the details of construction without departing from the principles herein set forth. 100

I claim:

1. The method of making composite structures by galvanoplastic process which comprises depositing a soluble material on portions of metallic sheet members to establish areas of integral contact with the metal to be deposited thereon, coating said sheet members with a conducting material for receiving a non-adhering metal deposit, dissolving the soluble material thereby exposing clean surface portions, and depositing galvanoplastic metal on the treated surface of the sheets integrally with said exposed surface portions. 115

2. The method of making composite structures by galvanoplastic process which comprises depositing a soluble material on portions of metallic sheet members to establish areas of integral contact with the metal to 120

be deposited thereon, coating said sheet members with a conducting material for receiving a non-adhering metal deposit thereon, depositing insulating material on said sheet members to establish non-conducting areas, dissolving the soluble material thereby exposing clean surface portions, and depositing galvanoplastic metal on the treated surface of the sheet members integrally with

10 said exposed surface portions.

3. The method of making radiators which comprises placing a plurality of metal sheets in superposed relation, temporarily joining said sheets with a resinous substance, applying a soluble substance externally of said sheets to form a plurality of narrow stripes on both sides and the edges of said metal sheets, coating said metal sheets on both sides with an electrical conducting material; 15 dissolving the said soluble material, submerging the treated metal sheets in an electrolytic solution to form a deposit of galvanoplastic material thereon, and subsequently bending the said metal sheets and 20 25 expanding the deposited metal thereon.

4. The method of making radiators which comprises applying a plurality of narrow stripes of a soluble substance on both sides of a metal sheet, coating said metal sheet 30 with an electrical conducting material, applying stripes of insulating material between some of the soluble stripes to form unjoined portions, dissolving the said soluble material, submerging the treated metal 35 sheet in an electrolytic solution to form a deposit of galvanoplastic metal thereon, and subsequently expanding the deposited metal.

5. The method of making radiators by galvanoplastic process which comprises placing a plurality of metallic sheet members in superposed relation, temporarily joining said sheet members with a resinous substance therebetween and depositing a soluble substance on portions thereof to establish areas of integral contact with the metallic deposit thereon, coating said members with a conducting substance for receiving metallic deposits, dissolving said soluble substance thereby exposing clean 45 50 surface portions, depositing non-conducting substances to establish unjoined portions and subjecting said sheet members to said galvanoplastic process to form metallic deposits on the treated surfaces integrally with 55 said exposed portions, subsequently shaping and expanding said sheet members and metallic deposits.

In testimony whereof I have hereunto set my hand this 30 day of April, 1930.

60 GUNNAR ROSENQVIST.
